(57) **CLAIM**

The ornamental design for a hood for a vehicle, as shown and described.

DESCRIPTION

This application contains subject matter related to the following co-pending U.S. design patent application:

Application Ser. No. 29/813,873, filed herewith and entitled “Motor Vehicle, Toy Replica, and/or Other Replica”.

FIG. 1 is a top view of a hood for a vehicle according to the design;

FIG. 2 is a front view thereof;

FIG. 3 is a right, front perspective view thereof, the left, front perspective view being a mirror image;

FIG. 4 is a right, rear perspective view thereof, the left, rear perspective view being a mirror image;

FIG. 5 is a right side view thereof, the left side view being a mirror image;

FIG. 6 is a rear view thereof; and,

FIG. 7 is a bottom view thereof.

1 Claim, 7 Drawing Sheets
